UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TWO-WEAVE LOOM DOBBY

Application filed December 1, 1927. Serial No. 237,071.

This invention relates to multiple weave pattern mechanisms for looms and it is the general object of the invention to provide a main pattern surface which may be varied 5 to meet different conditions to produce a variety of fancy weaves together with an auxiliary pattern surface which may, if desired, remain the same for all different forms of the main pattern surface, the auxiliary surface 10 providing a simpler form of weave to appear in those portions of the fabric lying between the fancy patterns which are woven by the main pattern chain.

In my prior Patent No. 1,060,977 there is 15 shown a so-called name dobby which has gone into general use for weaving names, trade-marks or other identifying legends in the selvages of fabrics. The dobby shown in that patent provides no means for incorporating the name forming warps into the cloth between the names and these warps remain 20 as floats which must be cut off before the fabric is ready for the market.

In my co-pending application Ser. No. 25 203,417 there is shown an improved form of name dobby wherein provision is made for attaching the name forming warp threads to the cloth at spaced intervals in the sections between the names, thus avoiding the necessity for shearing after the cloth is removed 30 from the loom. The auxiliary pattern surface shown in said application controls but one set of hooks so that it cannot be used to provide a second weave. The auxiliary pattern 35 surface shown in said application also moves about a fixed axis and for this reason there must always be a blank space running the length of the auxiliary surface which is presented to the hook controlling members 40 when the main pattern chain is active. It is found that this blank space limits the number of ways in which the selected warp threads 45 can be attached to the selvage.

It is an important object of my present 45 invention to provide means for moving the auxiliary surface so that when out of action it will be raised above the hook controlling members, thereby rendering unnecessary the blank space required in the aforesaid application. By operating on each set of hooks I

am able to control the warp threads for every pick of the loom and thus produce perfect weaves. Because of the fact that the upper cylinder in its present form is moved out of the range of the hook controlling members it 55 is not necessary that the multiplying intervals in picks between names be a multiple of the picks required for the revolution of the auxiliary pattern surface, although such a relation is necessary in the device shown in the 60 aforesaid application.

It is another object of my present invention to provide a simplified means for guiding the dobby fingers. As ordinarily made the outer ends of dobby fingers are reduced 65 to cooperate with a comb which guides the fingers and holds them in position for proper registry with the pegs on the dobby chain. I find that pressed steel fingers are so uniform that it is unnecessary to guide every individual finger, it being sufficient to make certain of the fingers shorter than the others to provide a space for a guide pin, one guide pin serving to properly locate several fingers.

It is a more detailed object of my invention 75 to make the cylinder on which the multiplying chains are located of laminations so that if desired the length of the cylinder may be increased to provide room for another multiplying chain.

Dobbies usually employ lifter wires which extend from certain of the fingers to the upper hooks to position the latter with respect to the upper knife. It is a further object of my present invention to extend these wires so 85 that they may have direct contact with the previously mentioned auxiliary pattern surface, said wires being so formed as to be controlled from two points and at the same time determining the position of the corresponding hook.

The dobby as set forth herein is designed primarily for controlling selvage threads and has no connection with the main pattern surface which determines the weave of the fabric 95 between selvages and it is a still further object of my invention to provide a loom having a main warp controlling mechanism such as a dobby in combination with a smaller additional pattern mechanism which itself is ca- 100

pable of providing a plurality of different weaves independent of the weaves provided by the main warp controlling device.

With these and other objects in view which will appear as the description proceeds, my invention resides in the combination and arrangement of parts hereinafter described and set forth in the claims.

In the accompanying drawings, wherein I have shown a convenient embodiment of my invention—

Fig. 1 is a side elevation of a dobby made according to my present invention with the main pattern chain operative and the auxiliary pattern mechanism moved to inactive position, certain parts being in section;

Fig. 2 is a rear elevation of the dobby looking in the direction of arrow 2, Fig. 1;

Fig. 3 is an operating view similar to a portion of Fig. 1 but showing the auxiliary surface lowered so as to be in hook controlling position;

Fig. 4 is an enlarged vertical section on line 4—4 of Fig. 2;

Fig. 5 is a rear elevation looking in the direction of arrow 5, Fig. 4, certain parts being in section;

Figs. 6 and 7 are detailed horizontal sections on lines 6—6 and 7—7, respectively, of Fig. 5;

Fig. 8 is an enlarged longitudinal section through a portion of the auxiliary pattern surface taken on line 8—8 of Fig. 1;

Fig. 9 is an enlarged end elevation looking in the direction of arrow 9, Fig. 2;

Fig. 10 is a vertical section on line 10—10 of Fig. 9;

Fig. 11 is an enlarged horizontal section on line 11—11 of Fig. 2;

Fig. 12 is a plan of one of the disks of which the auxiliary pattern surface is formed;

Fig. 13 is a diagrammatic front elevation of a loom showing the main dobby which controls the greater part of the warp threads and also the dobby forming the subject matter of the present invention, and

Fig. 14 is a fragmentary sectional view taken on line 14—14 of Fig. 1 showing the lock levers which lock the main patterns cylinder and multiplier chain.

Referring to Fig. 13 I have shown the relative positions of certain parts of the loom with respect to my present invention. As shown therein the loom frame L supports the main warp controlling device which may be a dobby D to control the harness frames H. The cords C lift the selvage warps to be controlled by my improved mechanism shown generally at G, although it is to be understood that the mechanism set forth herein can be employed to weave figures at points in the fabric intermediate the selvages.

My improved dobby is shown in Figs. 1, 2 and 3, where it will be seen that I have pro-

vided a dobby frame 10 supported preferably by the arch 11 of the loom and having mounted for rotation therein a dobby cylinder 12. Said cylinder may be provided with a pattern chain 13 preferably of the so-called double index type and have secured thereto a shaft 14 which extends through one of its bearings to have secured thereto a ratchet wheel 15. A pawl 16 is mounted on a stud 17 carried by an arm 18 secured to rock shaft 19. Said shaft 19 is given an oscillating movement by means of a connector 20 through the action of a cam or other suitable device not shown but operating so as to rock the shaft 19 in one direction on one pick and in the opposite direction on the next pick. In this way the pawl 16 is given an upward movement every alternate pick of the loom.

The mechanism for determining when the pawl 16 shall be operative to engage the ratchet 15 includes a multiplying unit M having a cylinder 21 rotatable on the shaft 14. Said cylinder carries a pair of multiplying chains 22 and 23, respectively, of different lengths, each of which is formed of a number of high links 24 and one low link 25. A lever 26 pivoted on a fixed stud 27 has a foot 28 broad enough to engage both of the chains. Said lever has at the upper end thereof a controller 29 which is adapted to cooperate with a broadened portion 30 of the pawl 16. So long as a high link on one or both of the multiplying chains is under the foot 28 the lever 26 will be held in the position shown in Fig. 1 with the controller 29 holding the pawl 16 outwardly to be inactive with respect to the ratchet 15, but when both of the low links appear under the foot the latter will move to the right as shown in Fig. 1 and the pawl 16 will move inwardly to have engagement with the ratchet wheel 15.

The harness cord controlling jacks 31 are each pivoted to a carrier lever 32 having pivotal connection with a fixed pin 33. Each carrier lever is pivoted to a back lever 34 at an intermediate portion of the latter, and each back lever is provided with a pair of hooks, one at each end, the upper hooks being indicated at 35 and the lower hooks indicated at 36. A rocking frame 37 secured to the shaft 19 has upper and lower knives 38 and 39, respectively, which act to move any hooks which may be in their paths as they rock back and forth.

The means for determining which of the hooks shall be engaged by the knives includes a set of fingers 40 pivoted on the stud 27. Certain of said fingers have upwardly and forwardly extending arms 41 for direct engagement with the lower hooks 36 while other of said fingers have normally horizontal arms 42 which cooperate with lifter rods 43 to raise and lower the upper set of hooks.

The multiplying cylinder has rigid there-

with a ratchet 44 positioned to be actuated by the vertically reciprocating pawl 45 pivoted on the pin 17. By means of a weighted portion 46 the pawl 45 is held against a stop 47 on a control lever 48 having shoe 49 to be acted upon by clip 50 carried by one of the links of the main pattern chain 13.

In the operation of the mechanism thus far described the pawl 16 will engage the ratchet 15 to produce an advance movement of the main chain 13 on each alternate pick of the loom. The pegs on the bars of said chain will raise selected fingers so that the corresponding hooks will be lowered and as the rocking frame 37 oscillates the lowered hooks will be moved to the right as viewed in Fig. 1, the upper hooks being moved on one pick and the lower hooks on the next pick, one angular movement of the dobby cylinder 12 determining the shedding for two successive picks of the loom. During this operation the lever 48 is in the down position shown in Fig. 1 with the stop 47 holding the pawl 45 out of engagement with the ratchet 44, but as the main chain continues to rotate to produce a fancy pattern the clip 50 will ultimately arrive under the shoe 49 to raise the lever 48 to the position shown in Fig. 3, whereupon the stop 47 will move to the right sufficiently to permit engagement of pawl 45 by ratchet 44. Clip 50 will effect the movements just described while pawl 16 is being raised on one pick and on the next succeeding pick pawl 45 will move downwardly to actuate the multiplier cylinder 21. The lever 26 which was previously positioned to permit pawl 16 to actuate the main cylinder will now be moved so that controller 29 will move to the right to disable the pawl 16, moving the same to the position shown in Fig. 1. On each alternate pick thereafter the multiplying element will be given a vibration and the pawl 16 will be held inactive until both low links again appear under the foot 28 of lever 26. During the operation of the multiplier the main pattern surface is at rest, but as soon as the multiplier has completed its counting of the picks during which the main chain is idle the latter will again come into action and on its first movement will move downwardly to render the pawl 45 inactive by reason of stop 47. The general construction thus far described together with the method of operation, may be substantially the same as set forth in my aforesaid Patent No. 1,060,977, to which reference may be had for a more extended explanation for the operation and uses of this portion of the device.

My present invention relates partly to the details of construction of the mechanism already described. As shown in Figs. 1, 2 and 3 certain of the fingers 40 are shorter than others and are indicated at 60. Spacing pegs 61 extend upwardly from a supporting bar 62, said pegs being in alignment with the

shorter fingers 60 and having lateral supporting relation with respect to the longer fingers which lie on each side of the shorter fingers 60. As shown particularly in Fig. 2 several of the full length fingers may be located between the pins 61. I find by this construction that the fingers are all properly located with respect to the pegs on the main pattern chain and that it is unnecessary to provide a guide peg for each finger as has been the usual construction heretofore. If desired the shorter fingers 60 may alternate with the longer fingers so that there will be but two types of fingers, namely the short fingers, with the arms 42 and the longer fingers 40 with the arms 41.

A detailed feature of my invention relates to the construction of ratchet 15 and the multiplying mechanism M. As shown in Fig. 11 the ratchet 15 may be formed of a plurality of flat disks 63 having toothed sections 64 together with other flat disk sections 65 which have depressions 66 to cooperate with a yielding lock lever 67 loosely pivoted on rod 27.

As shown in Fig. 10 the multiplying unit may have several disks 68 provided with depressions 69 which cooperate with a yielding lock lever 70. A single spring 71 common to both the yielding lock levers 67 and 70 tends to hold the ratchet 15 and the multiplying unit cylinder in proper position. Ratchet disks 72 similar to the disks 63 may form the multiplier ratchet 44. As shown in Fig. 3 other disks 73 having depressions 74 and projections 75 form the actuating cylinders for the chains 22 and 23. Said disks 73 may be separated into two groups which are defined by separating disks 76 all as shown in Fig. 10. Tie bolts 77 passing through all of the disks 68, 72, 73 and 76 bind the same into a unitary element rotatable on the shaft 14. The purpose of making the cylinder of disks or laminations is to permit the employment of as many multiplying chain sections as desired without requiring a different pattern for each different size of multiplying unit.

As previously stated my aforesaid co-pending application illustrates an auxiliary pattern surface which is designed to control the hooks while the main dobby chain is at rest, but the construction set forth therein has certain limitations which are overcome by my present invention. As shown herein I provide an auxiliary pattern surface which is to be raised out of controlling position when the main pattern surface is active but which is lowered so as to control the operation of the hooks when the main chain is at rest. Accordingly, I provide an auxiliary pattern surface designated generally at A and including a shaft 80 loosely rotatable in a pair of arms 81 which are pivoted for movement about a rod 82. The auxiliary pattern surface is located between the arms 81 and includes

a plurality of disks 83 each of which may be formed as shown in Fig. 12 with a plurality of equally spaced concentric openings 84 and a cam shaped controlling portion or projection 85. These disks may be as shown in my aforesaid application and are held together by means of tie rods 86.

The manner of attaching the disks to the shaft 80 is set forth in Fig. 8, where it will be seen that a slot 87 in the shaft 80 receives a key 88 fitting into a notch 89 formed in one of the disks 83. In this way the auxiliary surface formed of all the disks 83 rotates with the shaft 80.

As shown in Fig. 2 an actuating element 15 for the auxiliary surface is indicated at 90, being secured to the shaft 80 and having a ratchet 91 and a holding member 92 to cooperate with the yielding spring plunger 93 carried by one of the arms 81. An actuating pawl 94 for the auxiliary pattern surface is pivoted to the oscillating arm 18 at 95 preferably at a point between the shaft 19 and the pivot of the pawls 16 and 45. The reason for so locating the pivot of pawl 94 is that the auxiliary pattern surface as shown herein is designed to control 32 picks of the fabric being woven and must therefore be provided with sixteen angularly spaced controlling portions for the hooks. The ratchet 91 will therefore have sixteen teeth whereas the ratchet for the multiplying element will have eight so that the pawl 94 will need only half as much motion as do the pawls 16 and 45.

In order to determine when the auxiliary pattern surface shall be lowered and the pawl therefore rendered active I provide the lever 48 with an extension 100 which by means of an adjustable link 101 is connected to a rocking lever 102 pivoted loosely on the shaft 19. One arm of the lever 102 is pivotally connected as at 103 to a link 104 which extends upwardly to receive one end of the shaft 80 as shown in Figs. 1, 2, and 3. A second controller 105 is secured to the link 104 and is positioned for contact with pawl 94. The latter is provided with a weighted arm 106 which normally holds the pawl against the second controller. A tension spring 107 is interposed between the frame 59 of the device and some part of the linkage between lever 48 and link 104, preferably at the connection between arm 100 and link 101, said spring normally tending to hold the auxiliary cylinder in raised position.

The control devices for the hooks include the previously mentioned lifter rods 43 and additional lifter rods 108. As shown in Figs. 4, 5, 6 and 7 the lifter rods 43 extend upwardly to the guide frame 109 forming part of the comb 110 which guides the lower hooks 36. Said rods 43 extend upwardly and have a portion offset as at 111 to provide supports for the upper set of hooks 35. The upper 65 ends of said lifter rods are bent back on

themselves as at 112 to be received by short slots 113 formed in the upper guide 114.

The additional lifter rods 108 also extend through and are positioned by the guide 109 and have the upper ends thereof bent downwardly as at 115, the downwardly bent end being spaced from the main part of the additional wire as shown clearly in Figs. 4 and 6, spaced holes 116 being formed in pairs in the top guide 114 to receive each rod 108 and hold the same against angular displacement. The upper ends of both sets of rods are rounded as at 117 to cooperate with the projections 85 on the auxiliary pattern surface. The lower end of each of the additional rods 108 has a horizontally extending portion 118 which is received by a notch 119 in the corresponding arm 41. Said notch is deep enough so that the upper portion of the wire will not be engaged by the hook 36 which rests on the arm 41, thus preventing wearing of said wire.

It is to be understood that there are as many hooks as there are fingers, the lower hooks being controlled by the fingers having the arms 41 by direct engagement of said lower hooks with said arms while the upper hooks are controlled through the lifter rods 43 by the fingers provided with the arms 42.

In the operation of the mechanism spring 107 will act to hold the auxiliary pattern surface in raised position while the main dobby chain is weaving the name, trademark or other fancy weave to be incorporated into the selvage of the cloth, but as soon as clip 50 appears under shoe 49 the lever 48 will be raised, not only to start the operation of the multiplier as previously described, but also to move the auxiliary cylinder from the raised position shown in Fig. 1 to the low position shown in Fig. 3. This movement is accompanied by a motion of controller 105 to the left because of the fact that the link 104 also moves to the left, the result of which is that pawl 94 falls into actuating position with respect to the ratchet 91 and proceeds to rotate the ratchet and the auxiliary cylinder as the arm 18 oscillates. On each alternate pick of the loom the auxiliary pattern surface will be given an angular movement which as set forth herein is equal to 1/16th of a turn. The disks 83 are so located with respect to the upper ends of the lifter rods that as the projections 85 reach their lowest position they will depress the corresponding rods so that the hooks controlled by said rods may fall into the path of the knives 38 and 39.

The disks may be located in any desired order to produce a variety of weaves and I do not wish to be limited to the formation of the disks with a single projection 85. As the multiplier completes its counting of picks during which the auxiliary surface is to be active the pawl 16 will again become active as previously described and the clip 50 will

be moved from under the shoe 49 and spring 107 will raise the auxiliary pattern surface out of controlling position with respect to the lifter rods. The multiplier may hold the auxiliary pattern surface in action for any desired number of picks irrespective of the number of picks required for said auxiliary mechanism to complete its revolution because of the fact that the disks 83 are raised out of controlling position when the multiplier acts to restore control of the shedding to the main dobby chains. In this respect the device disclosed herein possesses an advantage over that shown in the aforesaid application although it is necessary in my present construction to have a blank bar on the main dobby chain under the fingers while the auxiliary pattern surface is in action.

From the foregoing it will be seen that I have provided a pattern mechanism for operating on selected warp threads wherein the auxiliary pattern surface is raised out of controlling position for the lifter rods so that the multiplying interval for the mechanism M may be selected irrespective of the number of picks required for the auxiliary pattern surface to make a complete revolution. Furthermore it will be seen that both sets of hooks are controlled so that the disks 83 may control every shed which is formed during the action of the auxiliary pattern surface. Again, it will be seen that the dobby fingers are spaced by an improved arrangement wherein one guide pin suffices for several fingers. Also, the multiplying cylinder is made of laminations or disks as is also the ratchet wheel for the main chain. The upper ends of the lifter rods are arranged for direct engagement with the projections 85, the latter being of sufficient proportions to give the hooks a proper movement without the intervention of such multiplying levers as are shown in my aforesaid application. It will also be seen by reference to Fig. 13 that the mechanism herein provides means for weaving two distinctive types of weaves in addition to the ordinary pattern device D of the loom.

Having thus described my invention it will be apparent that changes and modifications may be made therein by those skilled in the art without departing from the spirit and scope of the invention and I do not wish to be limited to the details herein disclosed, but what I claim is:

1. In a pattern mechanism for looms, a main pattern surface movable about a fixed axis, a set of fingers to cooperate therewith, an auxiliary pattern surface, means separate from the fingers to establish connection between the auxiliary pattern surface and the fingers, means to render the main pattern surface alternately operative and inoperative, and means to move and hold the auxiliary pattern surface out of controlling position

with respect to the connections when the main pattern surface is operative.

2. In a pattern mechanism for looms, a main pattern surface movable about a fixed axis, a set of fingers to cooperate therewith, an auxiliary pattern surface, connecting rods operatively connected to the fingers and having portions to be engaged by the auxiliary surface, means to render the main pattern surface operative, and means to raise the auxiliary pattern surface out of operative engagement with the portions of the rod adapted for engagement with said auxiliary pattern surface.

3. In a pattern mechanism for looms, a main pattern surface movable about a fixed axis, a set of fingers to be controlled by the main pattern surface, rods extending upwardly from said fingers operatively related to the latter, an auxiliary pattern surface to have operative contact with the upper ends of the rods at predetermined times, a support for the auxiliary pattern surface having a portion to lie in the path of and to be movable by a part of the main pattern surface, said part of the main pattern surface operating to effect movement of the auxiliary pattern surface out of operative position relatively to the upper ends of the rods.

4. In a pattern mechanism for looms, a main pattern surface movable about a fixed axis, a set of fingers to be operated by said main pattern surface, operating members extending upwardly from and operatively connected to the fingers, an auxiliary pattern surface normally out of controlling position with respect to the operating members, a movable support for the auxiliary pattern surface, and an element carried by the main pattern surface and effective to move auxiliary surface into engagement with the members, whereby the auxiliary pattern surface will control the fingers.

5. In a pattern mechanism for looms, a main pattern surface movable about a fixed axis, a set of fingers to be operated by said main pattern surface, members operatively connected to and projecting upwardly from the fingers, an upper auxiliary pattern surface formed of a plurality of disks, said pattern surface being capable of assuming a plurality of different angular positions and to be operatively related to the members in each angular position, there being at least one disk to have operative engagement with one of the members for each of the aforesaid angular positions of the auxiliary pattern surface, and means to render said pattern surfaces alternately effective to control the fingers.

6. In a pattern mechanism for looms, a set of dobby fingers, a pair of pattern surfaces alternately effective to control the dobby fingers, rods having offset lower portions to

be operatively related to certain of the fingers, said rods projecting upwardly from the fingers and having their upper ends bent back on themselves to have two substantially parallel spaced portions for each rod, and a 5 guide to receive the spaced portions of each rod to hold the same against substantial angular movement, that portion of the upper end of each rod intermediate the parallel 10 portions thereof to be engaged directly by one of the pattern surfaces.

7. In a pattern mechanism for looms, a set of fingers having projecting ends formed each with a recess, a set of hooks to be engaged by the projecting ends, there being one hook for each of the fingers having a projecting end, a rod having a portion received by the recess below the corresponding hook and projecting upwardly, an auxiliary pattern mechanism to act directly on the upper 15 end of the rod to control said hook, and a main pattern mechanism for the fingers also effective to control the hooks.

8. In a pattern mechanism for looms, a 20 pair of pattern surfaces, a set of dobby fingers, means to render said pattern surfaces alternately effective to control the fingers, upwardly extending rods operatively connected to the fingers and adapted for co- 25 operation with one of the pattern surfaces, said rods having their upper ends bent back on themselves to provide rounded upper ends to have direct engagement with one of the pattern surfaces, the bent back ends of alternate rods being spaced from the main part 30 of the rod a given distance, and the bent back ends of the intermediate rods being spaced a different distance from their corresponding rods, and a guide to receive the 35 upper ends of all the rods.

9. In a pattern mechanism for looms, a 40 set of dobby fingers, a pair of pattern surfaces to be alternately operative with respect to the fingers, rods projecting upwardly 45 from the fingers, the upper ends of alternate rods being bent back on themselves to have a downwardly projecting end spaced a given distance from the main part of said alternate rods, the intermediate rods also having 50 their ends bent back, the downwardly projecting ends of said intermediate rods being at a greater distance from the rods than is the case with the alternate rod, and a guide 55 having openings for the reception of said rods and their depending ends.

10. In a pattern mechanism for looms, a 55 main pattern surface movable about a fixed axis, a set of fingers to be operated by said main pattern surface, upwardly extending rods the lower ends of which are operatively connected to the fingers, the upper ends of 60 said rods being bent back on themselves to have spaced substantially parallel portions, a stationary guide to receive the parallel 65 portions of each rod and hold the same

against substantial angular movement, and an auxiliary pattern surface to have direct engagement at selected times with the upper ends of the rods to depress the latter.

In testimony whereof I have hereunto af- 70 fixed my signature.

ALBERT A. GORDON.
